[57] **CLAIM**

The ornamental design for a truck bed body, as shown and described.

DESCRIPTION

FIG. 1 is a side elevational view of a truck bed body showing my new design, the opposite side being a mirror image thereof;

FIG. 2 is a top plan view thereof;

FIG. 3 is an end elevational view thereof;

FIG. 4 is an end elevational view thereof opposite to that shown in FIG. 3; and

FIG. 5 is a cross-sectional view thereof taken on the line 5—5 in FIG. 1.

The broken line showing of a truck bed in the drawings is for illustrative purposes only and forms no part of the claimed design.
